TRANSMISSION CONTROL DEVICES ADAPTED AS A SWITCH

Arthur Hafford Cooke, Oxford, and Herbert Wakefield Banks Skinner, London, England, and Arthur Gowsell Ward, Chalk River, Ontario, Canada, assignors to English Electric Valve Company Limited, Chelmsford, England, a company of Great Britain

Application August 6, 1947, Serial No. 766,494
In Great Britain March 9, 1942

Section 1, Public Law 690, August 8, 1946
Patent expires March 9, 1962

20 Claims. (Cl. 250—13)

This invention relates to control devices for high frequency electrical oscillations, and has for its object to provide a control device adapted to serve as a switch by which the flow of high-frequency energy at a junction between two conductors (i. e. transmission lines and/or waveguides or sections of a transmission line or waveguide) is varied either at will or automatically when its power exceeds a predetermined level.

According to the invention a switch for controlling the flow of high-frequency energy at a junction between two conductors (i. e. transmission lines and/or waveguides or sections of a transmission line or waveguide) comprises a resonator adapted to be coupled to said conductors and associated with an envelope containing gas or vapour in which a glow discharge can be excited, said switch serving during such glow discharge to vary the flow of energy between said conductors. The transmission control device may also be employed so that in its normal or non-ionized state, it prevents the flow of power into a line section or other part of a transmission system, and upon being ionized it effects the flow of power into the line section.

Preferred embodiments of the invention will now be described with reference to the accompanying diagrammatic drawings, in which:

Figure 1 is a schematic longitudinal cross-sectional view of a switch according to the invention, showing the use of the switch in connection with a particular radio application;

Figure 2 is a view similar to Figure 1, except that a waveguide is used in place of a transmission line on the input side of the switch;

Figure 3 is a cross-sectional view on the line A—A of Figure 2;

Figure 4 is a detailed longitudinal cross-sectional view of a preferred construction; and

Figure 5 is an end elevation of the device shown in Figure 4.

The principle of operation of the switch will now be described with reference to Figures 1 to 3. The resonator 1 is associated in a manner more fully described in a later part of the specification with a glass container or envelope 2 carrying the gas and/or vapour in which the discharge is excited; part of the resonator, terminating in the poles 3, 3a, is located within the container 2, while part is located outside. As shown in Figure 1, the input side 4 and output side 5 of a transmission line (said sides constituting two conductors or two sections of a transmission system) are coupled by means of loops 6 and 6a to the said outside part of the resonator, whereas as shown in Figures 2 and 3 the input side 4 is replaced by a hollow waveguide 7, rectangular in cross-section, into which the resonator opens directly through an aperture 8. It will be understood that if desired a waveguide may

be used on both the input and output sides; or on the output side only, in conjunction with a transmission line on the input side as shown in Figure 1. The advantage of using a waveguide on the input side is that, if considerable power is being employed, it obviates the possibility that would exist with a concentric transmission line, of sparking occurring between the inner and outer conducting portions thereof.

The resonator 1 is tuned to the frequency of the oscillations which are to be transmitted, and is thus set into resonant oscillation by the energy fed into it from the transmission line 11 or from the waveguide 7. In the absence of any glow discharge this energy passes to the output side 5 with very little loss, but when such a discharge is excited this exerts a powerful damping effect upon the oscillations in the resonator 1 and the amount of energy passing to the output side 5 is thereby substantially reduced. In the particular construction under consideration the resonator is constituted by a rhumbatron of toroidal form, as will be seen from Figures 1 and 2.

The value of a toroidal rhumbatron resonator for the purpose of the present invention resides in its high circuit magnification; circuit magnification (which is generally denoted by the symbol Q) is defined by Hensen (Journal of Applied Physics, vol. 9, October 1938, p. 654) as "π times the ratio of the energy stored in the circuit to the energy lost per half cycle." The necessity for using a resonator of relatively high Q arises as follows: If a resonator of low Q were employed, it would be necessary to use relatively tight couplings between the resonator and the input and output sides of the transmission line or waveguide in order that a sufficiently high percentage of the input energy might be transmitted to the output side in the absence of a glow discharge. Under these

conditions the damping produced by a glow discharge would have a relatively small effect on the amount of energy passing to the output side, and the efficiency of the device as a switch would be small. If, however, a resonator of high Q is employed, comparatively loose couplings suffice to transmit energy through the resonator with very little loss in the absence of a glow discharge, but when such a discharge is excited these couplings are insufficient to transmit power efficiently in view of the heavy damping. Under these conditions most of the energy reaching the input coupling is reflected back into the transmission line or waveguide, and of the power entering the resonator very little is transmitted to the output side; so that the device may be used as a switch or cut-off.

When it is desired that the switch should operate automatically, it is so arranged that the input energy shall itself excite the discharge when such energy reaches a predetermined level, the supply of energy to the output side then being thereby interrupted or substantially reduced.

For example, the invention may be used in connection with radio transmission and reception systems of the kind used for determining the position of aircraft or other objects by means of radio echoes. In general, such systems comprise a transmitter adapted to produce a sharply defined beam of ultra-short wave radiation in the form of a series of pulses, and an associated receiver adapted to pick up the radiations which are reflected when the transmitted beam encounters the object to be detected. In such systems a common aerial may be used for both transmission and reception, and it is then clearly necessary to protect the receiver, which may incorporate a crystal or other easily damaged component, from direct excitation (and damage) by the transmitted pulses.

Such protection may readily be effected by the use of a switch according to the invention as shown in Figures 1 to 3. The transmitter 9 is connected to the aerial or

equivalent device 10 by a transmission line 11 (Figure 1) to which the input line 4 is connected, or by the waveguide 7 (Figures 2 and 3) which is coupled directly to the resonator 1 as previously described; in both cases the output transmission line 5 is connected to the receiver 12.

Each transmitted pulse or pulse train, in addition to passing direct to the aerial, serves to excite the glow discharge and thus causes the switch to operate automatically. When such excitation takes place, the action of the switch is to limit the signal reaching the receiver 12 to a value almost independent of the transmitter power, since the voltage between the poles 3 and 3a of the resonator cannot exceed that at which the discharge passes. As the latter voltage is almost independent of the discharge current, it follows that the voltage between the poles, and consequently the power fed to the output side 5, is almost independent of the input power. The chief effect of increasing the input power is to increase the discharge current. Most of the input power is reflected back because of the damping of the resonator 1 by the discharge. When no transmission is taking place the discharge ceases, and incoming signals picked up by the aerial 10 are passed on to the receiver 12 with very little loss. The device may obviously be used in this manner in any radio system employing a common aerial for transmission and reception.

For use of the switch non-automatically, the glow discharge may be excited by an external control (e. g. an electrode from which a discharge is caused to excite the glow discharge) applied in any convenient manner as hereinafter described. In this case any signal, however small, is reflected back from the resonator 1 during the discharge instead of being transmitted. Such an arrangement may be used if desired in connection with the radio application previously described, the external control being operated to protect the receiver during the periods of transmission and any other period in which reception is not required. For example, modulation pulses from transmitter 9 may be applied to the electrode 25 to excite the glow discharge during the transmission of each pulse.

A preferred construction according to the invention will now be described with reference to Figures 4 and 5. The resonator here takes the form of a rhumbatron located partly inside and partly outside the glass container or envelope 2, the said container being used as previously described to carry the gas or vapour in which the glow discharge is to be excited. Such a construction may be produced by sealing two copper members 13, 14, formed with central openings 15, between sections of glass tubing 16 which constitute the container or envelope 2, the parts of members 13, 14, within the tubing being flared towards each other to form the poles 3 and 3a of the rhumbatron and the outer edges of said members outside the tubing being clamped to a silvered metal ring 17 which completes the resonator.

The rhumbatron may be tuned by means of one or more tuning plungers 18, provided with locking nuts 19, which are inserted radially through the silvered metal ring 17. Furthermore the copper members 13, 14 may be thermally compensated, so that the gap between their poles 3 remains constant in spite of temperature changes. If a wave guide connection is employed, as described with reference to Figures 2 and 3, the aperture with which the wave guide communicates may be formed in the metal ring 17.

Energy may be fed to and from the switch device in known manner by means of concentric transmission lines whose inner and outer members are connected to the inner members 21, 23' and outer members 22, 22' of terminal devices 23, 23' which constitute respectively plug-and-socket members of a coupling system and are screwed into radial holes in the silvered metal ring 17 at any convenient points. The devices 23, 23' carry coupling loops 6, 6a which lie within the resonator 1 and may be rotated to adjust the coupling, after which they may be clamped in

any desired position by means of lock-nuts (not shown). Alternatively, if a wave guide transmission is employed, input and output couplings may be made by connecting the sections of the wave guide over suitable openings in the external part of the rhumbatron as previously described with reference to Figures 2 and 3.

The construction described above has a further advantage besides simplicity of manufacture, and ease of tuning and coupling of the resonator. A large volume of gas is contained in the envelope 2, so that "cleaning up" or absorption of the gas due to the discharge is unimportant. The presence of glass inside the resonator does not greatly reduce its efficiency, measured values of Q of 4,000 to 5,000 having been obtained.

The choice of gas or vapour for the filling, which is largely governed by the use to which the control device is to be put, will now be considered. It is clear that the less critical are the conditions under which the control device is required to operate, the wider is the field of choice, but in particular cases any or all of the following factors may be of importance:

(1) In the case where the switch operates automatically, the value or level of input power at which the discharge commences. In the radio application described above the device should pass the most powerful incoming signal which the receiver will normally be required to pick up, and cut off signals more powerful than this.

(2) The time interval between the application of an input power pulse and striking of the discharge. This factor is of importance when the device operates automatically since any delay in the commencement of the discharge may result in the passing on of excessive power to the apparatus to be protected.

(3) The time interval between the cessation of the input power pulse and the cessation of the damping effect, arising from the momentary persistence of effective ionization in the tube. In the radio application referred to it is important that this time-lag (de-ionization time) shall be as short as possible, since the receiver may be required to pick up echoes arriving a few microseconds after the transmitted pulse has been sent out.

In the case of this particular radio application it has been found that water vapour at a pressure of 3 to 10 mm. of mercury gives very satisfactory results, the discharge commencing at a suitable value of input power and the time lag involved in factor (3) being less than half a microsecond as against 10 to 20 microseconds for hydrogen, helium, argon or neon. Rapid recovery is also obtained when water vapour is mixed with other gases such as hydrogen or helium.

A convenient method of ensuring that the time lag covered by factor (2) shall be as small as possible is to arrange that there shall be some ionization in the gap between the resonator poles before the control impulse arrives. It has been found that this priming ionization may be produced by passing a steady discharge between the outside of the resonator and one or more suitable auxiliary electrodes fitted within the glass tube, such as the electrode 25 shown in Figures 1, 2 and 4. A radio-active deposit on such auxiliary electrode or electrodes, or on the inside of the resonator 1 near the poles, will also produce ionization in the gap between the poles; a deposit of mesothorium or radium or their products has been found suitable for this purpose. A source of light shining into the tube also serves to make the discharge begin by producing photo-electrons.

If the switch is to act non-automatically a construction generally similar to that described above may be employed, with the addition of a separate electrode from which a discharge is passed to the rhumbatron for the purpose of interrupting the flow of oscillatory energy. This electrode may comprise a rod (similar to that constituting the electrode 25) which is located axially with respect to the tube 2 and terminates at a sufficient distance from the poles 3 of the rhumbatron to ensure that

it does not itself pick up any appreciable amount of the oscillatory energy. For the efficient operation of the device as a switch it is desirable that the discharge shall be directed as closely as possible to the poles of the rhumbatron, and for this purpose an insulating tube 25a (e. g. of silica or glass) is preferably fitted over the end of the electrode and arranged to extend to the vicinity of the poles. The electrode 25 is connected to a voltage source, represented by battery 26, and the operation of the control device may be controlled by switch 27 which may be operated manually or by any suitable device.

For use at very short wavelengths (of the order of 3 centimetres) it may be found convenient to adopt a construction embodying a rhumbatron located wholly within the glass container. This involves departure from the disc-seal construction described above and is necessitated by the facts:

(1) That owing to the very small size of the rhumbatron at such wavelengths said disc-seal construction presents mechanical difficulties, and

(2) That at these wavelengths the dielectric losses which would result from the presence of glass within the rhumbatron are considerable. The rhumbatron may conveniently be connected to sections of a wave guide by openings covered by windows of glass or silica, but if desired a transmission line, suitably sealed through the glass container, may be employed.

The cavity resonator constitutes a tuned system in which the spaced metal surfaces surrounding and forming the two re-entrant poles of the resonator constitute the principal capacity of the system. The resonator is normally tuned to the energy supplied to it, but when the gaseous filling becomes ionized, the effective capacity between the two metal pole surfaces is changed to such extent that the system becomes de-tuned. Also, as already explained, the ionized discharge acts as a damping medium on the waves.

In the arrangements shown in Figures 1 and 2 the transmission control device is employed in a manner to effect transfer of energy from one part of the system to another part when the device is inert, but interrupts the flow of energy during the condition of discharge.

The transmission control device may also be employed so that in its normal or inert state it prevents the transmission of energy from one line section to another and when ionized would effect the transmission of energy. For example, referring to Figure 1, the transmission control device could be employed to normally prevent the flow of power from transmitter 9 to the load 10 by adjusting the length of the line section 4. If this line section has a length equal to one-quarter wavelength, substantially no energy will be transmitted from transmitter 9 to load 10 when the resonator is inert, but transmission would occur when the resonator is ionized. If the line section 4 is a half wavelength long, energy will be transmitted from source 9 to load 10 in the normal or inert state of the resonator but will be interrupted in the ionized state.

Referring to Figures 2 and 3, the resonator is shown connected by a slot in the broad side of the wave guide 7 and constitutes a series element. This arrangement normally prevents the transfer of power from source 9 to load 10 during the inert state of the resonator but effects transfer of power during the ionized state. The same operation takes place if the connection of the resonator to the broad side of the wave guide is by a stub having a length equal to one-half wavelength. If the connecting stub has a length of one-quarter wavelength, transfer of power from source 9 to load 10 occurs only when the resonator is inert and is interrupted when the resonator is ionized.

By connecting the resonator to the wave guide through a slot formed in the narrow side of the guide longitudinally thereof, the resonator acts as a shunt element, and would normally permit the transfer of energy from source

9 to load 10 during the inert state but would effectively short circuit the wave guide in the ionized state. If the connection to the narrow side of the wave guide is by way of a stub having a length equal to one-half wavelength, the operation is the same as described, but if the stub has a length equal to one-quarter wavelength, then the operation is reversed from that described.

What is claimed is :

1. A transmission control device comprising a cavity resonator having a pair of open ended, re-entrant poles, a sealed envelope of insulating material surrounding said poles within said resonator and containing an ionizable gaseous filling.
2. A transmission control device according to claim 1 and including a priming electrode mounted within said envelope outside of the cavity of said resonator and extending to a point adjacent one of said re-entrant poles.
3. A control device comprising a cavity resonator having a pair of spaced poles, at least one of said poles having a central opening forming an aperture in the wall of said resonator, a sealed envelope enclosing the space surrounding said aperture on the outside of said resonator, a priming electrode mounted within said envelope and positioned adjacent said aperture, and an ionizable gaseous medium filling said envelope and the space within said resonator.
4. A control device according to claim 3 wherein said ionizable gaseous medium comprises water vapor at a pressure of 3 to 10 millimeters of mercury.
5. In combination, an antenna, a high frequency transmitter connected to said antenna, a receiver, an enclosed-field wave guide connected between said receiver and said antenna, said wave guide comprising a cavity resonator tuned to the frequency of said transmitter and enclosing means for producing an ionized gaseous discharge at a low vacuum pressure within said resonator for controlling the propagation of waves through said guide, and means acting independently of the wave energy of said transmitter for controlling said last-mentioned means in accordance with a predetermined controlling influence.
6. In combination, an enclosed-field wave guide having dimensions for conducting propagated pulsed wave energy of a predetermined mode, a cavity resonator intercepting the continuity of said wave guide and having entry means for the said wave energy, said resonator having resonance disruption producing means therein for disrupting resonance and electrically reflecting large pulses of said pulsed wave energy, but allowing free passage of received energy between said large pulses, and a keep-alive electrode for speeding resonance disruption by said means.
7. A tuned ionic switch comprising a cavity resonator having conductive inside walls, and having an aperture through a wall thereof, a gas-tight closure mounted in said aperture and sealing the same, said closure being composed of a material transparent to electromagnetic waves, a pair of discharge electrodes mounted inside said resonator, and a filling of ionizable gas enclosed by the said walls and closure of the resonator.
8. In combination in a duplex signaling system, a signal wave pulse generator, a signal receiver, a common antenna connected to said generator for radiating the signal pulses produced by said generator and for picking up incoming wave pulses, means connecting the input of said receiver to said antenna including a resonant chamber tuned to the frequency of the outgoing wave pulses produced by said generator and to the frequency of the incoming wave pulses picked up by said antenna, a spark gap connected across said resonant chamber, adapted to arc to effectively short circuit said chamber, and thus to effectively reduce the voltage input to said receiver, in response to the resonant voltage applied to said chamber by each signal pulse transmitted from said generator to said antenna, and to remain in the non-arcing condition in response to the relatively lower resonant voltage applied to said chamber by the incoming

signal pulses received by said antenna during intervals between transmitted pulses, so as to provide a minimum of attenuation to said incoming pulses in transmission to the receiver during said intervals, and means to maintain a keep-alive discharge adjacent said spark gap during said intervals.

9. In a system for radio transmission and reception over an antenna system common to a transmitter and a receiver, enclosed-field waveguides connecting said transmitter and said receiver to said antenna, a cavity resonator tuned to the frequency of said transmitter and interposed in the waveguide connecting said receiver to the antenna, an electrical discharge gap enclosed in said resonator and located therein at a position where oscillations of the aforesaid frequency produce voltages greater than the voltages appearing where said resonator is coupled to the waveguide in which it is interposed, said discharge gap being provided with means for maintaining an atmosphere of water vapor in said gap at partial vacuum pressure and being adapted to break down and thereby practically to short circuit said resonator when oscillations of said frequency exceed a predetermined amplitude, and means for establishing a keep-alive discharge adjacent said discharge gap.

10. In combination, an enclosed-field wave guide having dimensions for and conducting propagated pulsed wave energy of a predetermined mode, a resonator intercepting the continuity of said wave guide and having entry means for the said wave energy, longitudinal spark-gap electrodes coaxial with said resonator and constituting spark producing means for passing an electrical discharge therebetween thereby disrupting resonance and electrically reflecting large pulses of said pulsed wave energy, but allowing free passage of received energy between said large pulses, and a keep-alive electrode for one of said gap electrodes.

11. A TR box comprising a hollow-body resonator, opposed spark-gap electrodes in said resonator, one of said electrodes being tubular, and a keep-alive electrode mounted within said tubular spark-gap electrode.

12. A tuned ionic switch comprising a cavity resonator having conductive inside walls and having an aperture therein, a gas-tight closure mounted in said aperture and sealing the same, said closure being composed of a material transparent to electromagnetic waves, a pair of discharge electrodes mounted inside said resonator on opposite portions of the walls thereof, and a filling of ionizable gas enclosed by the said walls and closure of the resonator.

13. A tuned ionic switch comprising a cavity resonator having walls with conductive inside wall surfaces and having a glass window in a wall thereof, said window being hermetically sealed, a pair of discharge electrodes mounted inside said resonator and a filling of ionizable gas enclosed by the said walls and gas-tight window of the resonator.

14. An electrical discharge device for protecting a sensitive circuit from overloads caused by oscillations of a predetermined frequency including a resonant cavity transformer tuned to said frequency having low impedance input and output circuits and an electrical discharge gap across said resonant transformer at a location of relatively high voltages when said transformer is excited at said frequency adapted to break down when excited oscillations in said transformer exceed a predetermined amplitude, and thereby to short-circuit said input and output circuits of said transformer, said resonant transformer being adapted to transform oscillatory voltages appearing in said input circuit upwardly to said discharge gap and to transform oscillatory voltages across said gap downwardly to said output circuit, means to maintain the space between said poles at a partial-vacuum pressure to reduce the break-down voltage of said gap, and means to maintain a continuous keep-alive discharge adjacent one of the poles of said gap.

15. A transmission control device comprising a cavity resonator having a pair of aligned poles embodied in opposite wall sections thereof, and an ionizable gaseous medium comprising water vapor filling the space between said poles at a pressure greatly less than atmospheric pressure, said resonator being adapted when excited by waves of its resonant frequency to establish an arc discharge across said poles when said waves exceed a predetermined amplitude.

16. A transmission control device comprising a cavity resonator containing a pair of aligned poles embodied in opposite wall sections thereof, and an ionizable gaseous medium comprising a mixture of water vapor and hydrogen filling the space between said poles at a pressure greatly less than atmospheric pressure, said resonator being adapted when excited by waves of its resonant frequency to establish an arc discharge across said poles when said waves exceed a predetermined amplitude.

17. A transmission control device comprising a cavity resonator containing a pair of aligned poles embodied in opposite wall sections thereof, an ionizable gaseous medium filling the space between said poles at a pressure greatly less than atmospheric pressure, said resonator being adapted when excited by waves of its resonant frequency to establish an arc discharge across said poles when said waves exceed a predetermined amplitude, and means for maintaining a continuous keep-alive discharge adjacent one of said poles.

18. A transmission control device comprising a cavity resonator having a pair of aligned poles embodied in opposite wall sections thereof, an ionizable gaseous medium comprising water vapor filling the space between said poles at a pressure greatly less than atmospheric pressure, said resonator being adapted when excited by waves of its resonant frequency to establish an arc discharge across said poles when said waves exceed a predetermined amplitude, and means for maintaining a continuous keep-alive discharge adjacent one of said poles.

19. An electrical discharge device for protecting a sensitive circuit from overloads caused by oscillations of a predetermined frequency including a resonant cavity transformer tuned to said frequency having low impedance input and output circuits, an electrical discharge gap across said resonant transformer at a location of relatively high voltage when said transformer is excited at said frequency and adapted to break down when excited oscillations in said transformer exceed a predetermined amplitude and thereby to short-circuit said input and output circuits of said transformer, said resonant transformer being adapted to transform oscillatory voltages appearing in said input circuit upwardly to said discharge gap and to transform oscillatory voltages across said gap downwardly for energy transfer to said output circuit, and means for maintaining a partial vacuum in the space surrounding said electrical discharge gap, said means including at least one wall portion of non-conducting material sealed to the structure of said resonator at a location such that relatively low voltage stresses are caused to occur in said wall portion as the result of said oscillations.

20. In combination in a duplex signalling system, a signal wave pulse generator, a signal receiver, a common antenna connected to said generator for radiating the signal pulses produced by said generator and for picking up incoming wave pulses, means connecting the input of said receiver to said antenna including a resonant chamber tuned to the frequency of the outgoing wave pulses produced by said generator and to the frequency of the incoming wave pulses picked up by said antenna, a spark-gap connected across said resonant chamber, adapted to arc to effectively short-circuit said chamber, and thus to effectively reduce the voltage input to said receiver, in response to the resonant voltage applied to said chamber by each signal impulse transmitted from said generator to said antenna, and to remain in the non-arching condition in response to the relatively lower resonant voltage applied

to said chamber by the incoming signal pulses received by said antenna during intervals between transmitted pulses, so as to provide a minimum of attenuation to said incoming pulses in transmission to the receiver during said intervals, means to maintain the space between the poles of 5 said spark-gap at a partial-vacuum pressure to reduce the break-down voltage of said gap, and means to maintain a continuous keep-alive discharge adjacent one electrode of said spark-gap.
